HOLLOW METAL DOOR CONSTRUCTION

Earl Boughton, Canton, Ohio

Application May 13, 1948, Serial No. 26,768

12 Claims. (Cl. 189—46)

1

This invention relates to hollow sheet metal doors of the kind intended to be mounted on hinges for use in the doorways of buildings.

In the production of metal doors of this kind as heretofore carried out, the manufacturing operations have been slow and cumbersome and frequently have required the use of considerable hand labor and the use of special tools and equipment. The rate of production for such metal doors has accordingly been low in relation to the man-hours of labor consumed and in relation to the capital invested in tools, dies and other equipment. This has been particularly true in regard to providing reinforcements on metal doors to adapt them for the mounting of hinges and locks thereon, because these reinforcements have heretofore usually required careful fitting and assembly operations which greatly increase the labor costs and frequently can be carried out only by the use of special tools and equipment.

As its principal object, this invention provides a novel method of manufacture and an improved construction for metal doors of the character indicated, by which the rate of production of such doors can be greatly accelerated and the cost of the manufacture decreased correspondingly.

Another object is to provide a novel method and improved construction for metal doors in which preformed component door parts are assembled in two groups so as to form two similar units or subassemblies on which the various cooperating connecting portions are exposed and readily accessible for performing welding operation thereon with conventional welding equipment, and which units are then assembled in complementary relation to form a hollow door structure and are welded together in such complementary relation by a welding tool inserted into the hollow door structure.

A further object is to provide a novel method and improved construction for metal doors in which preformed sheet metal panels are assembled in two groups to form two similar pan-like units on which the cooperating portions of adjacent panels are exposed and readily accessible for performing welding operations thereon, and which pan-like units are then assembled in complementary relation to form a hollow door structure and are welded together by a welding tool inserted into the hollow door structure.

Yet another object is to provide an improved metal door construction of the character mentioned in which the preformed panels of each

2

unit include a hinge-stile panel and a lock-stile panel having cut-away portions to provide hinge-butt and door-lock recesses, and in which reinforcements are welded in place in the hinge-stile and lock-stile panels adjacent the cut-away portions thereof prior to the assembly of said units in said complementary relation to form the hollow door structure.

Still another object is to provide an improved door construction of this character in which the reinforcements and the portions of the hinge-stile and lock-stile panels with which they cooperate are so formed that the reinforcements will be self-locating in the panels and can be quickly and easily assembled therein with a minimum labor requirement without need for any fitting operations and when thus assembled will be accurately positioned and readily accessible for carrying out welding operations thereon with facility and by the use of conventional welding equipment.

As another of its objects, this invention provides an improved metal door construction of the character mentioned in which the reinforcements of the respective units form complementary parts of a connecting means by which the units are connected together to form the hollow door structure.

Other objects and advantages of this invention will be apparent in the following detailed description and in the accompanying sheets of drawings in which:

Fig. 1 is a side elevation showing a hollow metal door embodying the improved construction and which has been produced by the novel method of this invention;

Fig. 2 is a perspective view showing one of the pan-like units or sub-assemblies used in forming the improved metal door;

Fig. 3 is a transverse section taken through the door, as indicated by line 3—3 of Fig. 1;

Figs. 4 and 5 are partial vertical sections taken through the top and bottom edges of the door, as indicated by lines 4—4 and 5—5, respectively, of Fig. 1;

Fig. 6 is a partial side elevation showing the reinforced construction by which the door is adapted for the mounting of a hinge butt thereon;

Fig. 7 is a partial side elevation similar to Fig. 6, but with the hinge butt omitted;

Fig. 8 is a partial vertical section taken through the door adjacent one of the hinge mounts, as indicated by line 8—8 of Figs. 1 and 6;

Fig. 9 is a partial edge view of the door show-

ing one of the hinge mounts as formed by the hinge reinforcing elements, but with the hinge butt removed;

Fig. 10 is a face view showing the complementary hinge reinforcing elements in detached relation;

Fig. 11 is a partial vertical section taken adjacent the lock reinforcement, as indicated by section lines 11—11 of Figs. 1 and 12 and showing the door lock installed in the metal door;

Fig. 12 is a partial vertical section taken on the irregular section line 12—12 of Fig. 11 and presenting a face view of one of the lock reinforcing elements;

Fig. 13 is a partial transverse section taken through the door above the lock reinforcement as indicated by line 13—13 of Fig. 11, the door lock being shown only in construction lines;

Fig. 14 is a perspective view of a portion of one of the lock-stile panels with its lock reinforcing element assembled therein;

Fig. 15 is a partial edge view of the door showing the lock reinforcement and the lock-receiving recess, but with the lock removed;

Fig. 16 is a perspective view similar to Fig. 14, but showing a modified form of lock reinforcing element;

Fig. 17 is a partial edge view of the door showing the lock reinforcement and lock-receiving recess provided therein by the modified lock reinforcing elements, but with the lock removed;

Fig. 18 is a partial transverse section taken through the door above the modified lock reinforcement, as indicated by line 18—18 of Fig. 17;

Fig. 19 is a transverse section similar to Fig. 3 but taken through another modified form of the improved hollow metal door; and

Fig. 20 is a partial end view of a conventional welding tool adapted for insertion into the hollow door structure in carrying out the novel method.

The improved hollow metal door 10 comprises a pair of generally flat shallow pan-like units or sub-assemblies 11 and 12 which have substantially smooth flat outer faces forming the side faces 13 and 14 of the door and which units are connected together in face-to-face complementary relation as shown in Fig. 3 to form the hollow door structure. The units or sub-assemblies 11 and 12 are similar in construction and each comprises a group of preformed sheet metal panels disposed in coextending relation and having their adjacent edges connected together. In this instance each unit comprises three such preformed sheet metal panels consisting of the edge or stile panels 15 and 16 and an intermediate or body panel 17. In the completed door the edge panel 15 forms a portion of the stile of the door on which the hinge butts 18 are mounted and for that reason can be conveniently referred to as a hinge-stile panel. Similarly, the edge panel 16 forms a portion of the stile on which the door lock mechanism 19 is mounted and can therefore be referred to as a lock-stile panel.

Since the pan-like units 11 and 12 are similar in construction and are composed of similar groups of corresponding identical preformed sheet metal panels, it will only be necessary to describe in detail one of these units, such as the unit 11. The hinge-stile panel 15 is of a substantially C-shaped cross-section having reversely bent edge portions which form thereon the longitudinal edge flanges 20 and 21 and the in-turned longitudinal edge flange extensions 22 and 23 which are hereinafter referred to as connecting

flanges. The edge flanges 20 and 21 extend rearwardly at substantially right angles to the flat sheet or web 24 forming the outer face of this panel. The lock-stile panel 16 is also of C-shaped cross-section and has reversely bent edge portions forming thereon the longitudinal edge flanges 25 and 26 which extend rearwardly at substantially right angles to the flat plate or web portion 27 and the in-turned longitudinal flange extensions 28 and 29 which are herein-after designated connecting flanges.

The intermediate panel 17 is a channel-shaped panel having a substantially flat plate or web portion 30 and longitudinal edge flanges 31 and 32 extending at substantially right angles thereto. In forming the unit 11 the panels 15, 16 and 17 are disposed in side-by-side co-extending relation with the flat web portions 24, 27 and 30 thereof lying in substantially the same plane. The edge panel 15 is connected to the intermediate panel 17 by welding the flanges 20 and 31 together. Similarly, the edge panel 16 is connected to the intermediate panel 17 by welding the edge flanges 26 and 32 together. The welding of these pairs of flanges can be easily and rapidly carried out by conventional welding apparatus adapted to form rows of spot welds 33 and 34, because at this time these pairs of flanges are exposed and readily accessible.

The units 11 and 12 have longitudinal and transverse plan dimensions which correspond respectively with the dimensions of the door 10 in height and width. These units also have a depth or thickness substantially equal to one-half of the thickness of the door. The units 11 and 12 are assembled with their open or recessed sides in face-to-face complementary relation to form the hollow door structure, as mentioned above, which brings the connecting flanges 22, 23, 28 and 29 of the two units into paired relation and in face-to-face engagement with each other, as shown in Fig. 3. When the units 11 and 12 have been thus assembled, the cooperating hinge-stile panels 15 of the two units define a longitudinal passage 35 in the door structure and, similarly, the cooperating lock-stile panels 16 and the cooperating intermediate panels 17 form longitudinal passages 36 and 37.

The units 11 and 12 are connected together in this complementary relation by rows of spot welds 38, 39, 40 and 41 formed on the paired connecting flanges 22, 23, 28 and 29. The welding of these connecting flanges together can be carried out by the use of conventional welding apparatus which is inserted, in succession, into the passages 35 and 36 by movement endwise of the door structure. For this purpose a welding apparatus can be used having a relatively long thin flat beam portion which is provided at the end thereof with a pair of arms 42 and 43, as shown in Fig. 20, carrying cooperating welding contacts or electrodes 44 and 45. In welding apparatus of this type one of the arms, such as the arm 42, is pivoted for swinging movement relative to the other arm to cause opening and closing of the electrodes. This swinging movement can be produced by a rock shaft 46 which extends longitudinally of the beam portion of the apparatus.

The hollow door structure formed by the complementary units 11 and 12, as described above, can be reinforced and the ends of the passages 35, 36 and 37 thereof can be closed by the use of channel members 47 and 48 at the top and bottom edges of the door. These channel mem-

bers can be recessed into the top and bottom edges of the door, as shown in Figs. 4 and 5, and can have their flanges connected to the sides 13 and 14 of the door by rows of spot welds 49.

Before the hinge-stile panels 15 are incorporated into the units 11 and 12, they are notched to provide partial hinge butt recesses and are also provided with hinge reinforcing elements 50 and 51 which form partial hinge butt mounts and together constitute the hinge mount 52 (see Fig. 9). Likewise, before the lock-stile panels 16 are incorporated into the units 11 and 12 they are notched to provide partial lock-receiving recesses and are also provided with lock-reinforcing elements 53 and 54 forming partial door-lock mounts which together constitute a door-lock mount 55 (see Figs. 11, 13 and 15). The mounting of the hinge- and lock-reinforcing elements on the panels 15 and 16 prior to these panels being incorporated into the units 11 and 12 is very important because, at this time, the panels are still open such that the reinforcing elements can be quickly and easily assembled therein and can be welded in place by welding operations which require only the use of conventional welding equipment. These hinge- and lock-reinforcing elements 50, 51 and 53, 54 and the mounting thereof on the panels 15 and 16 will now be described in greater detail.

As shown in Fig. 9 of the drawings, the hinge-stile panels of the respective units 11 and 12 have notched recesses or openings 56 and 57 formed therein. The opening 57 of the unit 12 extends through the edge flange 21, but does not extend across the full width of this flange. The opening 56 of the unit 11 extends entirely across the flange 21 and for a short distance into the flat plate or web portion 24 of the hinge-stile panel 15. The portions of the connecting flanges 23 lying between the top and bottom edges 58 and 59 of these openings are entirely cut away as is clearly indicated in Figs. 6, 7 and 8. The two openings or partial recesses 56 and 57 of the units 11 and 12 are complementary to each other and together form a hinge butt recess 18a in which the butt 18 is mounted, as shown in Figs. 6 and 8.

The hinge-reinforcing elements 50 and 51 are elongated strip-like plates which are mounted in the respective units 11 and 12 against the inner faces of the edge flanges 21 thereof and in longitudinal spanning relation to the partial recesses 56 and 57. The reinforcing element 50 has substantially flat connecting portions 50a and 50b at the ends thereof which are in face-to-face engagement with the inside of the edge flange 21 of the unit 11 and are connected thereto by the spot welds 60. The intermediate portion 50c of the reinforcing element 50 is offset from the plane of the end portions and cooperates with the edge flange 21 of the unit 11 to give the hinge recess 18a a depth approximately equal to the thickness of the plate portion of the hinge butt 18. Similarly, the reinforcing element 51 is provided with end portions 51a and 51b which are spot welded to the flange 21 of the unit 12 and with an offset intermediate portion 51c.

As shown in Fig. 10 the intermediate portion of the reinforcing element 51 is somewhat wider than the intermediate portion of the reinforcing element 50. When the reinforcing elements are assembled in the door structure as shown in Fig. 9 and the units 10 and 11 are brought into their complementary relation, these intermediate portions have matching engagement along their

adjacent edges as represented by the irregular line or joint 61. The joint 61 is so formed that it includes the offset matching portions 61a and 61b and when the reinforcing elements are in the proper position longitudinally of the door, these matching portions will register with each other. The hinge-reinforcing elements 50 and 51 are provided with groups of tap openings 62 and 63, there being three such openings in each group and the openings of each reinforcing element being spaced apart equal distances longitudinally of the element and also being spaced inwardly the same distance from the joint 61.

As shown in Figs. 9 and 10 of the drawings, the ends 50a and 50b of the hinge-reinforcing element 50 and the ends 51a and 51b of the reinforcing element 51 are somewhat narrower than the intermediate portions of these elements and are of a width to fit snugly into the panels 15 against the inner faces of the edge flanges 21 thereof. Because the paired end portions 50a, 51a and 50b, 51b of the hinge-reinforcing elements 50 and 51 are of this reduced width they define therebetween the longitudinal slots 64, as shown in Fig. 25, which accommodate the paired connecting flanges 23 of the panels 15 when the units 11 and 12 are in assembled position, as shown in Fig. 9. The portions 64a of the hinge-reinforcing elements 50 and 51 which define the inner ends of 30 the slots 64 cooperate with the edges of the cut-away portions of the connecting flanges 23 for locating the reinforcing elements longitudinally of the panels 15, as is also shown in Fig. 9. From the shape and arrangement just described above 35 for the notched recesses 56 and 57 of the hinge-stile panels 15 of the units 11 and 12 and for the hinge-reinforcing elements 50 and 51, it will be seen that these reinforcing elements will be self-locating in the panels 15 with respect to the partial recesses 56 and 57 thereof and, when the units 40 11 and 12 are assembled in their face-to-face complementary relation, the reinforcing elements will form the hinge mount 52 lying inwardly of the recess 18a and whose end slots 64 straddle the 45 adjacent portions of the paired connecting flanges 23.

By providing the hinge reinforcing elements 50 and 51 with three of the tap openings 62, 63, the hinge mount 52 will be adapted for the mounting 50 of the hinge butt 18 thereon regardless of whether this butt is a so-called "template" butt or a "non-template" butt. The hinge butt 18 is here shown as being connected with the mount 52 by means of two screws 62a engaging in the two end tap 55 openings 62 of the reinforcing element 50 and a single screw 63a engaging in the center tap opening 63 of the reinforcing element 51. When the hinge butt 18 is connected to the mount 52 as just described, it will be observed that the butt acts as a strap or plate which spans the joint 61 between the two reinforcing elements 50 and 51. It will thus be recognized that the elements 50 and 51 reinforce the hinge-stile panels 15 of the units 11 and 12 at the point where these panels are notched to form the hinge recess and they also form complementary joint elements which are connected by the hinge butt 18 to strongly tie the units 11 and 12 together at this point.

The hinge mount 52 is here shown as having 70 longitudinal slots 65 therein which are exposed on the edge of the hinge-stile of the door 10 prior to the mounting of the hinge butt 18 thereon. These slots afford openings into which a conveyor hook or other work handling means can engage 75 for lifting or handling the door. The slots 65

are desirable for this purpose although they can be omitted when not required.

From the shape of the hinge-reinforcing elements 50 and 51 and the shape and location of the partial openings 56 and 57 of the panels 15 of the units 11 and 12, as above described, it will be seen that these hinge-reinforcing elements will be substantially self-locating in the panels during the operation of assembling them therein. This saves much time and expense because no cutting or fitting operations are needed. Moreover, as mentioned above, the panels 15 are still open at this time which facilitates the assembly of the hinge-reinforcing elements 50 and 51 therein and permits the welding of these elements in place to be carried out rapidly and by the use of conventional welding equipment.

As shown in the drawings, the lock-stile panels 16 of the units 11 and 12 have their edge flanges 25 notched to provide partial recesses 65 and 66 therein which together form a lock-receiving recess 67 in the corresponding edge of the door 10 adapted to accommodate the door-lock 68, as shown in Fig. 11. The lock-stile panels 16 of the units 11 and 12 are provided respectively with the above-mentioned reinforcing elements 53 and 54 which reinforce these panels at the point of their partial recesses 65 and 66 and together form the mount 55 for the lock 68. As also mentioned above, the lock-reinforcing elements 53 and 54 are assembled in the panels 16 and welded in place therein prior to the incorporation of these panels in the respective units 11 and 12. When the reinforcing elements are put into the panels 16 at this time, the panels are open such that the reinforcing elements can be quickly and easily assembled therein and can be readily welded in place by the use of conventional welding apparatus. It is also important that the shape of the reinforcing elements is such that these elements will be self-locating in the panels 16 and this will permit these elements to be assembled in place in the panels with a minimum labor expenditure and without need for any cutting or fitting operations. The lock-receiving recess 67 of the door structure and the lock mount 55 formed by the reinforcing elements 53 and 54 will now be described in greater detail.

As best seen in Figs. 14 and 15 of the drawings, the partial recesses 65 and 66 of the lock-stile panels 16 of the units 11 and 12 extend part way across the edge flanges 25 and extend entirely through the connecting flanges 28 as an interruption or gap in the latter. These partial recesses 65 and 66 are complementary to each other and together form the lock-receiving recess 67 in the edge of the door and with which recess the gap of the flanges 28 is substantially longitudinally coextension. This recess is of a length and width to snugly receive the face plate 70 of the lock mechanism 68 as shown in Figs. 11 and 12.

The lock reinforcing elements 53 and 54 are made of sheet metal and are identical in construction such that they can be produced from the same dies. Each of these reinforcing elements is provided with a substantially flat body portion 71 and with a pair of angularly disposed arms 72 and 73 adjacent its ends. Each element is also provided with a pair of angularly disposed connecting and positioning lugs 74 and 75, preferably right-angle lugs, located adjacent the arms 72 and 73. When the reinforcing elements 53 and 54 are assembled in the panels 16, the flat plate portions 71 are disposed in engagement with and welded to the inner sur-

face of the flat web portions 27 of these panels. The welds formed for this purpose are here represented by the spot welds X.

When the lock-reinforcing elements 53 and 54 are located adjacent the partial recesses 65 and 66 of the panels 16, the angular arms 72 and 73 seat against the inner faces of the edge flanges 25 of the panels and in the door structure formed by the units 11 and 12 these arms of the reinforcing elements are in paired relation straddling the connecting flanges 28, as shown in Figs. 11 and 13. The spacing of the connecting lugs 74 and 75 is such that the remote edges of these lugs engage the portions of the connecting flanges 28 which are located at opposite ends of the partial recesses as shown in Fig. 14. The arms 72 and 73 and the connecting lugs 74 and 75 thus provide positioning members by which the reinforcing elements 53 and 54 can be quickly and accurately positioned in the panels 16 and will be substantially self-locating therein by the mere insertion of these reinforcing elements in the respective panels.

When the units 11 and 12 are assembled in their complementary relation to form the hollow door structure, as explained above, the connecting lugs 74 and 75 of the reinforcing elements 53 and 54 extend into overlapping relation with each other, as shown in Figs. 11 and 13. Each of the lugs 75 has a tap opening 76 therein and each of the lugs 74 has a somewhat larger clearance opening 77 therein. The position of these lugs in the assembled door structure is such that the lugs 74 overlie the lugs 75 and the clearance openings 77 expose the tap openings 76. The tops of the lugs 74 and 75 are offset slightly inwardly from the tops of the arms 72 and 73 and when the connecting lugs are in their overlapping relation, as shown in Fig. 13, they will form the above-mentioned mount 55 for the door lock 68.

By reason of the inwardly offset relation of the connecting lugs 74 and 75 the mount 55 formed thereby will be located relative to the edge of the door such that when the lock 68 is assembled in position, the face plate 70 thereof will be substantially flush with the edge face of the door. The lock 68 is secured in place by screws 78 which extend through the face plate 70 and through the clearance openings 77 and engage in the tap openings 76. When the lock is assembled in this position, the screws 78 also form an interlock for the paired connecting lugs 74 and 75 of the reinforcing elements 53 and 54, thus providing a strong connection between the units 11 and 12 at this point.

As shown in the drawings the lock-reinforcing elements 53 and 54 are provided with a pair of openings 79 and 80, one of which accommodates the rotary spindle 81 of the door-lock 68 on which the door knob 82 is mounted. The other of these two openings is located opposite the key-hole of the escutcheon plate 84. When the reinforcing elements 53 and 54 are welded in place in the panels 16 the spot welds X are so located that some or all of them will be hidden by the escutcheon plate 84 on the knob side of the door and by the escutcheon member 85 on the opposite side of the door. At a point intermediate the openings 79 and 80 the reinforcing elements 53 and 54 are provided with inwardly offset partially sheared strips or fingers 86 which serve as a locating means for the lock 68 and prevent shifting or rattling thereof. The reinforcing members 53 and 54 are also provided with suit-

ably located tap openings 87 to accommodate screws 88 by which the escutcheon members 84 and 85 are mounted on the door.

Figs. 16, 17 and 18 show a modified construction for a pair of complementary lock-reinforcing elements 90 and 91. The lock-reinforcing elements 90 and 91 are similar to the lock-reinforcing elements 53 and 54 above described and are used in the same manner and for the same purpose. The reinforcing elements 90 and 91 differ from the reinforcing elements 53 and 54 in that the interlock between the pair of complementary reinforcing elements is obtained in the modified construction by the use of tongue and slot elements in addition to the screws which connect the door lock to the lock mount.

The modified lock-reinforcing elements 90 and 91 carry angularly disposed connecting lugs 92 and 93 which correspond in location and function with the above described connecting lugs 74 and 75. The lug 92, however, is provided with an inwardly deflected tongue or finger 94 and the lug 93 is provided with a slot 95 adapted to snugly receive one of the fingers 94. When the units 11 and 12 are assembled in their complementary relation to form the hollow door structure, the lugs 92 extend in overlying relation to the lugs 93 with the fingers 94 engaging in the slots 95. The engagement of the fingers in these slots provides an interlock between the reinforcing elements 90 and 91 and enables these elements to more strongly reinforce the door structure at the lock recess. The lugs 93 have tap openings 93a therein and when the door lock is mounted on the door by screws engaging in these openings, the screws also form an interlock between the paired reinforcing elements 90 and 91.

As shown in Fig. 16, the connecting lugs 92 and 93 of the reinforcing elements 90 and 91 are provided with extension lugs 96 and 97 which extend toward the arms 72 and 73 and engage behind the connecting flanges 28. The extension lugs 96 and 97 are of a size to fit snugly between the flanges 28 and the flat plate portions 27 of the panels 16. These extension lugs thus cooperate with the connecting flanges 28 for assisting in locating the reinforcing elements in proper position in the panels 16 and also for the purpose of holding the edge flanges of the panels against deflection.

Fig. 19 shows another hollow metal door 100 which is a modification of the door 10 described above. From a comparison of Fig. 19 with Fig. 3 it will be observed that the modified door 100 is also formed by a pair of preformed complementary units or sub-assemblies 11 and 12 and that each of these units comprises a pair of stile panels 15 and 16 and an intermediate or body panel 17. In the modified door 100, however, these panels are of a somewhat different cross-sectional shape by reason of the fact that the paired connecting flanges 101 and 102 are carried by the intermediate panels 17 instead of by the stile panels.

In this modified door 100 each of the intermediate panels 17 is generally channel-shaped in cross-section but has the longitudinal connecting flanges 101 and 102 formed at the sides thereof as out-turned extensions of their longitudinal edge flanges 31 and 32. When the units 11 and 12 are disposed in face-to-face relation the connecting flanges 101 of the two intermediate panels 17 are in surface engagement with each other and form a longitudinal rib which

projects into the longitudinal passage 36 formed by the stile panels 16. Similarly, the connecting flanges 102 of the panels 17 are in surface engagement with each other and form a longitudinal rib which projects into the longitudinal passage 35 formed by the stile panels 15. The paired flanges 101 are connected together by longitudinally spaced welds 103 and the paired flanges 102 are connected together by similar welds 104.

The modified construction of Fig. 19 will provide a door 100 which is very strong and rugged and which will be well suited for use as a fire door. The ribs formed by the paired connecting flanges 101 and 102 will greatly strengthen the intermediate portion of the door which is formed by the panels 17 and will enable this portion to better resist the stresses which develop when the door is subjected to heat.

From the foregoing description and the accompanying drawings it will now be readily understood that the present invention provides a novel construction and method of manufacture for hollow sheet metal doors in which groups of panels are first welded together to form pan-like units and the units thus formed are then connected in complementary relation to form the hollow door structure. It will also be understood that this invention provides a novel construction and method in which hinge- and lock-reinforcing elements are provided in the door with a minimum expenditure of labor in assembling and welding the elements in place and with substantially no cutting or fitting operations being needed during the assembly work. In connection with these reinforcing elements it will be further understood that they are of a novel construction which renders them self-locating in the panels during assembly and which results in an interlock between these elements for strongly reinforcing the door structure at the location of its hinge- and lock-receiving recesses. Additionally, it will be recognized that in the novel method and construction herein disclosed most of the welding is carried out while the parts are in an open and exposed condition which permits the welding to be carried out easily and rapidly with conventional welding apparatus and only a small part of the welding is required to be performed internally of the hollow door structure.

Having thus described my invention, I claim:

1. In a sheet metal door, a hollow stile having opposed side walls and an edge wall defining a longitudinal edge face of the door, an internal longitudinal flange carried by said edge wall and projecting from the inner surface thereof, said edge wall having an opening therein interrupting said flange and adapted to receive the plate portion of a door-lock having plate and body portions, and a reinforcement located in and reinforcing said stile at the location of said opening, said reinforcement comprising a pair of complementary one-piece plate members having angular lug portions extending across said opening in a spaced apart relation longitudinally of the opening to accommodate the body portion of said door-lock therebetween, said angular lug portions comprising a front lug and a rear lug on each plate member lying inwardly of the plane of said edge face with the front lugs extending in overlapping relation to the rear lugs such that said angular lug portions form a mount adapted for the attachment of the plate portion of said door-lock thereto, said angular lug portions also

11

forming locating elements and being in engagement with said flange at said interruption thereof for locating said plate members relative to said opening and longitudinally of said stile and said plate members being welded to said side walls.

2. In a sheet metal door, a hollow stile having opposed side walls and an edge wall defining a longitudinal edge face of the door, said edge wall having an opening therein adapted to receive the plate portion of a door-lock having plate and body portions, and a pair of complementary reinforcing plates welded in place in said stile and against said side walls substantially at the location of said opening and adapted to accommodate the body portion of said door-lock therebetween, said reinforcing plates each having a front lug and a rear lug extending across said opening adjacent the ends thereof but lying inwardly of the plane of said edge face and forming a mount adapted for the attachment of the plate portion of said door-lock thereto, said front and rear lugs being in paired overlapping relation and the rear lugs of the pairs having tap holes therein and the front lugs having clearance holes therein exposing said tap holes.

3. In a sheet metal door, a hollow stile having wall means including opposed side walls and an edge wall defining a longitudinal edge face of the door, internal flange means carried by said edge wall and projecting inwardly therefrom, said edge wall having an opening therein extending through said edge face and interrupting said internal flange means and forming a recess adapted to receive the plate portion of a door-lock having plate and body portions, and a pair of complementary reinforcing plates welded in place in said hollow stile and against said side walls substantially at the location of said recess and adapted to accommodate the body portion of said door-lock therebetween, said reinforcing plates each having a front lug and a rear lug extending across said recess adjacent the ends thereof but lying inwardly of the plane of said edge face and forming a mount adapted for the attachment of the plate portion of said door-lock thereto, said front and rear lugs being in paired overlapping relation and said rear lugs having tap holes therein and said front lugs having clearance holes therein exposing said tap holes, said reinforcing plates being located in said stile longitudinally thereof and relative to said recess by engagement of the lugs of said plates with said internal flange means at the interruption thereof and said reinforcing plates also having flange portions seated against the inner face of said edge wall and locating said paired lugs in the inwardly lying relation to the plane of said edge face.

4. In a sheet metal door, a hollow stile having wall means including opposed side walls and an edge wall defining a longitudinal edge face of the door, said edge wall having an opening therein extending through said edge face and forming a recess adapted to receive the plate portion of a door-lock having plate and body portions, and a pair of complementary reinforcing plates located in said stile and having paired lugs extending across said recess adjacent the ends thereof and inwardly of the plane of said edge face and forming a mount adapted for the attachment of the plate portion of said door lock thereto, said reinforcing plates being welded in place in said stile by attachment to the side walls thereof and said paired lugs having cooperating tongue and

12

slot elements interlocking said reinforcing plates with each other.

5. In a sheet metal door, a hollow stile having wall means including opposed side walls and an edge wall defining a longitudinal edge face of the door, said edge wall having an opening therein extending through said edge face and forming a recess adapted to receive the plate portion of a door-lock having plate and body portions, and a pair of complementary reinforcing plates welded in place in said stile adjacent the location of said recess by attachment to said side walls and adapted to accommodate the body portion of said door-lock therebetween, said reinforcing plates each having a front lug and a rear lug extending across said recess adjacent the ends thereof but lying inwardly of the plane of said edge face and forming a mount adapted for the attachment of the plate portion of said door-lock thereto, said front and rear lugs being in paired overlapping relation and said rear lugs having tap holes therein and the front lugs having clearance holes therein exposing said tap holes, said paired lugs also having cooperating tongue and slot elements thereon interlocking said reinforcing plates with each other.

6. In a sheet metal door, a hollow stile having wall means including opposed side walls and an edge wall defining a longitudinal edge face of the door internal flange means carried by said edge wall and projecting inwardly therefrom, said edge wall having an opening therein extending through said edge face and interrupting said internal flange means and forming a recess adapted to receive the plate portions of a door-lock having plate and body portions, and a pair of complementary reinforcing plates welded in place in said hollow stile at the location of said recess and against said side walls and adapted to accommodate the body portion of said door-lock therebetween, said reinforcing plates each having a front lug and a rear lug extending across said recess adjacent the ends thereof but lying inwardly of the plane of said edge face and forming a mount adapted for the attachment of the plate portion of said door-lock thereto, said front and rear lugs being in paired overlapping relation and said rear lugs having tap holes therein and said front lugs having clearance holes therein exposing said tap holes, said reinforcing plates being located in said stile longitudinally thereof and relative to said recess by engagement of the lugs of said plates with said internal flange means at the interruption thereof and said reinforcing plates also having flange portions seated against the inner face of said edge wall and locating said paired lugs in the inwardly lying relation to the plane of said edge face, said paired overlapping lugs having cooperating tongue and slot elements interlocking said reinforcing plates with each other.

7. In a sheet metal door, wall means defining a hollow stile having a longitudinal edge face thereon and also having internal flange means carried by said wall means and projecting inwardly therefrom, a hardware member, said wall means having an opening therein extending through said edge face and interrupting said internal flange means and forming a recess adapted to receive said hardware member, a reinforcement in said stile adjacent the location of said recess and having portions spaced inwardly from the plane of said edge face and forming a mount for said hardware member, said reinforcement comprising a pair of complementary one-piece

plate members welded in place on said wall means and having portions thereof engaging said flange means at the interruption thereof for locating said plate members in said stile and relative to said recess, said hardware member being disposed in said recess and having one face thereof lying in substantially flush relation to the surface of said edge face and the opposite face lying against said mount, and means securing said hardware member to said mount.

8. In a sheet metal door, a hollow stile having a longitudinal passage therein and also having walls including a pair of opposed side walls and an edge wall defining a longitudinal edge face of the door, an internal longitudinal flange carried by said edge wall and projecting from the inner surface thereof into said passage, said edge wall having an opening therein communicating with said passage and said flange having a gap therein substantially longitudinally coextensive with the edge wall opening, said opening and gap being adapted to receive a door lock, and a combined hardware mount and stile reinforcement means comprising a pair of complementary one-piece metal plate reinforcement members disposed in said passage and having substantially right-angle lug locating portions thereon adjacent opposite ends of said reinforcement means and engaging said flange at the ends of said gap for positioning said reinforcement members longitudinally in said passage and relative to said opening, said reinforcement members being secured to said side walls by welded connections and having said right-angle lug locating portions thereof exposed through said opening and forming a mount for said door lock.

9. In a sheet metal door, a hollow stile having a longitudinal passage therein and also having walls including opposed side walls and an edge wall defining a longitudinal edge face of the door, an internal longitudinal flange carried by said edge wall and projecting from the inner surface thereof into said passage and being spaced from said side walls by longitudinal channel portions of said passage, said edge wall having an opening therein communicating with said passage and interrupting said flange and adapted to receive a hinge butt, and a pair of metal plate members having relatively close fitting engagement in said channel portions and also having locating portions engaging said flange at said interruption thereof for locating said plate members longitudinally of said channel portions and relative to said opening, said plate members being welded to said edge wall in spanning relation to said opening and having portions exposed

through said opening and forming a mount for said hinge butt.

10. Sheet metal door structure as defined in claim 9 in which said plate members have edge portions in an interfitting meeting engagement within the interruption of said flange.

11. In a sheet metal door, a hollow stile having a longitudinal passage therein and also having walls including an edge wall defining a longitudinal edge face of the door, an internal longitudinal flange carried by said edge wall and projecting from the inner surface thereof into said passage, said edge wall having an opening therein communicating with said passage and interrupting said flange and adapted to receive a hinge butt, and a pair of complementary one piece metal plate stile reinforcement members disposed in said passage and having locating portions engaging said flange at said interruption thereof for positioning said reinforcement members relative to said opening, said reinforcement members being secured to said edge wall in spanning relation to said opening and having portions thereof exposed through said opening and forming a mount for said hinge butt, said reinforcement members have preformed tap holes therein and which tap holes are located so as to provide two different groups of such tap holes adapting said mount to receive either of two hinge butts having differently grouped fastening holes.

12. Sheet metal door structure as defined in claim 8 in which said internal flange divides said longitudinal passage of the stile into coextending channel portions and in which said reinforcement members have angular lug portions forming locating elements extending into said channel portions and seating against the inner surface of said edge wall adjacent opposite ends of said opening.

EARL BOUGHTON.
